UNITED STATES PATENT OFFICE.

ROBERT LUCIEN D'ESPUIJOLS, OF LA VARENNE ST. HILAIRE, FRANCE.

BOILER.

Application filed April 16, 1920, Serial No. 374,428, and in France April 24, 1919.

This invention relates to boilers and in particular to an improved semi-instantaneous vaporizing tubular boiler, characterized by the new arrangement of its tubular system. The boiler of the present invention is intended to develop great power with a very small volume, especially when applied to a motor car, for example. It is therefore essential for the boiler to have a large heating surface compared with its volume. This result is attained, as will be explained later, by a special arrangement of tubes. Moreover, the tubes are arranged in such a manner that the gases of combustion from the fire are retained as long as possible in the tubular system, so that they may be deprived of their heat, while allowing the gases a sufficient section of passage to enable combustion to proceed in normal conditions. Thus a maximum utilization of the heat produced in the furnace is attained.

A form of construction of the boiler is shown in the accompanying drawings.

Fig. 1 is a front elevation of the device, partly in section,

Fig. 2 is a section on the line 2—2 in Fig. 1;

Fig. 3 is a side elevation, partly in section, showing the arrangement of the tubular system comprising tubular elements each of which consists of four tubes marked I, II, III and IV.

Fig. 4 is a view, in elevation, of a fragment of an element showing tube I unobstructed in view by II, III or IV.

Fig. 5 shows the arrangement of the four tubes of an element, seen in plan; and

Figs. 6, 7, 8, 9 are plans of tubes Nos. IV, III, II, and I respectively, shown separated one from the other.

The tubular system of the boiler is arranged as follows to realize the conditions of working described later.

(1) To utilize the greatest number of tubes possible in the space available, all the tubes lie in adjacent vertical planes and are stepped in height, at equal distances from each other. When viewed in plan (Fig. 2) the tubes of the system appear rectilinear and contiguous from end to end having between them only the necessary play for mounting, the ends appearing looped. They all appear viewed in elevation (Fig. 1) as coiled with uniform inclination to produce natural circulation of the steam. The

loops connecting the ends of the straight parts of the tubes have the same inclination as the straight parts thereof. Owing to this the steam formed in the bottom parts of the boiler tends to acquire a uniformly accelerated ascensional movement.

(2) The tubes are arranged in groups of four expanded at their ends in boxes 5, 5' inclined at 45° with respect to a plane passing through the axes of the four tubes (see Figs. 1 and 2).

Each group or element of the system comprises four tubes and two junction boxes 5 and 5' (Fig. 1) the latter being connected by means of conical nozzles and the tubes 2 and 4 with the steam chest 1 and the feed water collector 3 respectively. Thus each element can be detached from the boiler by unscrewing the union pieces 17 and 17'. Thus a group or element of the system can be replaced with remarkable ease. Threaded plugs 18 and 18' positioned opposite the ends of each tube permit expansion of the ends and cleaning of the interior.

To allow the combustion gases to give up their heat as completely as possible and also leave them a sufficient passage to find their way to the exit or chimney, adjacent tubes are inclined alternatively in opposite directions to each other, in such a manner that although all the tubes appear in plan to be longitudinally contiguous (Fig. 2) the apparently contiguous parts of any two adjacent tubes have really only one point of contact; their arrangement is also such that the gases which ascend vertically in the conduits or passages between the two consecutive tubes No. III always meet a tube No. I around which they have to pass in the free spaces left above. Increase of incline facilitates circulation of the combustion gases, owing to increase of the aforementioned spaces. Decrease of this incline evidently has the opposite effect; for with no inclination the tubes would be contiguous throughout their length and the draught be completely suppressed.

Each element of the system comprises four similar tubes I, II, III, IV (Figs. 6 to 9). These tubes are alike in pairs, tube I being similar to tube IV and tube II to tube III. The extremities alone differ at the point of connection with the boxes. The loops of tubes I and IV are completely offset with respect to the plane of the tube

and those of tubes II and III are partially so, in such a way that when the tubes I, II, III and IV are brought close alongside one another all the loops will overlap each other very exactly and be concentric.

In the mounting of the tubes on their boxes, corresponding portions of tubes I and III, and of tubes II and IV lie in two different planes spaced apart horizontally by one thickness of tube as shown in Fig. 2, the two horizontal planes in question being distant to an extent equal to half the pitch of the coil or spiral so as to obtain the points of contact in the middle regions of the tubes.

Moreover the first and last branches of the tubes III, IV, are slightly modified so that the loops of these tubes, at mounting, will be placed exactly under and almost in contact with the corresponding loops of tubes I, II. The four tubes thus formed are then brought close together in the order I, II, III, IV until all their loops are concentric and their ends are finally expanded in their boxes, so as to form an element.

The outside diameter of the loops should be equal to four times the diameter of a tube plus a certain play which may be equal to one tenth the diameter of the tube.

Briefly, the invention consists in a semi-instantaneous vaporizing boiler, for all applications, with a small volume of water, characterized by the organization of the tubular system formed of elements arranged on the one hand to develop great power with a very small volume and, on the other hand, to allow maximum utilization of heat produced in the furnace, retaining the gases of combustion as long as possible in the tubular system and allowing them also a sufficient section of passage for combustion to take place in normal conditions.

What I claim and desire to secure by Letters Patent of the United States is:—

1. A boiler, comprising a lower water drum, an upper steam drum, and a steam generating section interconnecting said water drum and steam drum, said section comprising a plurality of tubes, junction boxes for the ends of the tubes, each tube having a plurality of rectilinear portions arranged in a single vertical plane in zig-zag formation, looped portions inter-connecting the ends of said rectilinear portions, the rectilinear portions of the several separate tubes lying in closely adjacent parallel planes and the loops at the corresponding ends of the several separate tubes being arranged vertically one directly above the other.

2. A boiler, comprising a lower water drum, an upper steam drum, and a steam generating section interconnecting said water drum and steam drum, said section comprising, a plurality of separate tubes, each tube having a plurality of rectilinear portions arranged in a single vertical plane in zig-zag formation with looped portions inter-connecting the ends of said rectilinear portions, the rectilinear portions of the several separate tubes lying in closely adjacent planes with the rectilinear portions of one tube being inclined oppositely to the corresponding rectilinear portions of an adjacent tube, the loops at corresponding ends of the several separate tubes being arranged vertically one directly above the other.

3. A boiler, comprising a lower water drum, an upper steam drum, a plurality of closely adjacent parallel steam generating sections interconnecting said water and steam drums, each section comprising a plurality of separate tubes, each tube consisting of a plurality of rectilinear portions arranged in a single vertical plane in zig-zag formation with looped portions inter-connecting the ends of said rectilinear portions, the rectilinear portions of the several separate tubes lying in closely adjacent parallel planes and the loops at corresponding ends of the several tubes being arranged vertically one directly above the other, a junction box for the corresponding ends of the tubes of each section, and means for detachably connecting said junction boxes to the water and steam drums respectively.

4. A steam boiler comprising, a feed water collector, a steam chamber, tube bundles positioned to be washed by heating gases and connected between the feed water collector and the steam chamber, each tube bundle consisting of four separate pipes which extend in separate vertical planes, each pipe being placed zig-zag with a slight pitch in the form of a flattened helical line, the four pipes when viewed from above lying closely adjacent each other, a housing for each end of each bundle of tubes, a connection pipe connecting each housing to the water collector and the steam chamber respectively, each housing being positioned so that the line of connection between the housing and the separate pipes is at an angle of 45° to the axes of the separate pipes.

Signed at Paris, France, this 31st day of March 1920.

ROBERT LUCIEN D'ESPUIJOLS.
